CLOTHES HANGER

Carl E. Gingher, 304-328 Depot St., Scranton, Pa.

Filed July 19, 1965, Ser. No. 86,198

Term of patent 14 years

(Cl. D80—8)

This is a continuation-in-part of design application Serial No. D.79,704 filed April 27, 1964, now abandoned.

The characteristic feature of my design resides in the portions shown in full lines.

I claim:

The ornamental design for a clothes hanger, as shown and described.
